(57) **CLAIM**

The ornamental design for a dual voltage electrical assembly, as shown and described.

DESCRIPTION

FIG. 1 is a perspective view of one embodiment of the dual voltage electrical assembly of our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a front view of an alternative embodiment of the dual voltage electrical assembly of our new design, with the remaining views of this alternative embodiment being the same as those presented in FIGS. 3-7.

The broken line showings of FIGS. 1-8 are for illustrative purposes only and form no part of the claimed design.
